UNITED STATES PATENT OFFICE.

ADRIAN P. SCHMIDT, OF NEW YORK, N. Y.

EXERCISING APPARATUS.

No. 839,040.

Specification of Letters Patent.

Patented Dec. 18, 1906.

Application filed May 11, 1906. Serial No. 316,233.

To all whom it may concern:

Be it known that I, ADRIAN P. SCHMIDT, a subject of the German Emperor, and a resident of the borough of Manhattan, in the city of New York, county and State of New York, have invented certain new and useful Improvements in Exercising Apparatus, of which the following is a specification, reference being had to the accompanying drawings, forming a part thereof.

My invention relates to improvements in exercising apparatus, and particularly to weight-lifting means.

My invention consists in an exercising-machine comprising weight-lifting devices which are readily variable under the direct control of the user, and it comprises many novel combinations of parts and details of construction, such as will be better understood by the explanation in detail of a complete apparatus in which the invention is embodied. I will therefore proceed to describe in detail such an apparatus, having reference to the accompanying drawings, in which same is illustrated, and will then point out the novel features in claims.

In the drawings, Figure 1 is a view in central vertical longitudinal section through the exercising-machine. Fig. 2 is a transverse sectional view thereof substantially upon the plane of the line 2 2 of Fig. 1. Fig. 3 is a detail sectional view upon the plane of the line 3 3 of Fig. 1. Fig. 4 is a detail sectional view on the plane of the line 4 4 of Fig. 1. Fig. 5 is a detail view in longitudinal section through certain parts, including the pivoted housing for the weighted lever and certain correlated parts. Fig. 6 is a face view of a scale employed, together with certain parts, including indicating-fingers arranged to register with such scale. Fig. 7 is a perspective view of the entire machine on a much-reduced scale.

The casing of the machine comprises a base 1, end and side walls 2 3, and a platform 4. A lever 5 is pivoted at 6 to brackets 7, supported upon the base 1 of the casing, the said lever provided at its outer end with a heavy spherical weight 8. Above the lever 5 is another lever 9, which I will herein term the "intermediate" lever. This intermediate lever is pivoted at 10 to a bracket 11, secured to one of the end walls 2 of the casing. The bracket 11 is provided with a projecting abutment 12, which limits the downward movement of the said lever, supporting it

normally in substantially a horizontal position. A link 13 is arranged to connect the two levers 9 and 5 together, the said link 13 being provided near its upper end with an opening 14, by which it may be caused to engage at will with any one of a series of studs 15, laterally projecting from the lever 9, and at its lower end being forked, as at 16, and provided with a transverse bolt 17, whereby it will readily engage the said lever 5 in any one of the various positions to which it may be adjusted.

A third lever 18 is provided, the said lever being mounted in a housing 19, which housing is pivoted at 20 to brackets 21, mounted on a portion of the platform 4 or other part stationary with the casing. The said lever 18 is fitted freely within the housing 19, being permitted to pass longitudinally therethrough. The outer end of the lever 18 is provided with a yoke or fork 22, to which is pivotally suspended a weight 23. The said weight has a part 24, which projects downwardly and is provided at its lower end with a hook-like portion 25, adapted to engage with teeth 26 upon the lever 9. When the parts are in their normal rest position, as they are shown in the drawings, the hook 25 is just out of engagement with the teeth 26, whereby the lever 18, with the weight 23 and rod 24, may be freely moved longitudinally without hindrance from any engagement with the lever 9. The moment the weighted end of the lever 18 is lifted, however, the hook 25 will be caused to engage with the teeth 26 of the lever, and a further upward movement of the weighted end of the lever can only be made against the resistance of the lever 9 and any parts connected thereto. The part 24 preferably comprises a rod which passes clear through the weight 23, terminating at the upper end in a handle 38.

If desired, by manipulation of the handle 38 the hook portion of the handle 25 may be turned to such a position as to be out of the path of the teeth 26 of the lever 9, so as to be adjusted to a position wherein it is entirely independent in its movement of the intermediate lever 9 and the weighted lever 5. When in such position, the lever 18, with its weight 23, may be lifted without the resistance offered by the weight 8.

Surrounding the housing 19 is a yoke 27, the said yoke preferably being caused to laterally engage shouldered portions 28 upon the housing, as will be readily understood by ref-

erence to Figs. 1 and 3 of the drawings. This engagement of the yoke with the housing will prevent any accidental movement of the said yoke lengthwise of the housing—*i.e.*, 5 toward and away from the pivotal center 20. To the upper end of the yoke is secured a handle 29, and to the said handle or other part fast to the yoke is attached a harness 30.

In using the apparatus the operator may 10 conveniently stand upon the platform 4 and either grasp the handle 29 or fit the harness 30 to himself, whereupon he may carry out such weight-lifting exercises as may be desirable. Stationary handles 31 are provided, 15 secured to the platform 4, which may be employed when the harness is used and the hands are thus otherwise free.

The yoke 27 carries two pawls 32 and 33, pivoted thereto at 34, the said pawls being 20 adapted to engage with rack-teeth 35 upon the under side of the lever 18. The said pawls and rack-teeth when properly engaged constitute feeding means for the lever 18. The casing 19 is open at the bottom, so that 25 the teeth of the pawls 32 and 33 will be free to engage the said teeth. The said pawls are weighted, as will be seen, so that their normal tendency will be to swing inward toward an upright position. Stops 36 are provided, the same comprising screws threaded 30 into the sides of the yokes and arranged to engage inclined surfaces 37 (see Fig. 3) of the pawls. By screwing in any one of these stops all the way one or other of the pawls 35 will be thrown out of operative position, while by properly adjusting the other of said pawls the extent of movement of the said other pawl will be regulated as may be desired.

40 When it is desired that both pawls shall be thrown out of operative position, both studs may be screwed all the way in, also an abutment 39 may be caused to engage the upper face of the housing 19, so that the yoke and 45 pawls will have no relative movement with respect to the said housing when the same is raised and lowered. When the abutment 39 is turned out of engagement with the housing 19, the yoke 27 will have some vertical 50 movement between the shoulders 29 and either one or other of the pawls 32 33, which ever is so adjusted, will be permitted to operate. This operation will be as follows: Upon the downward movement of the yoke one of 55 the said pawls—say, for instance, pawl 33—will be allowed by gravity to swing to a somewhat more vertical position—that is, the end which engages the teeth 35 of the lever 18 will swing inward toward the yoke. Then 60 upon a lifting movement the said pawl 33 will impart a feeding movement forward to the lever 18, the said lever moving through the housing 18, as above explained, for this purpose, and the pawl 33 returning to the 65 limit of its outward movement. By this

means the weight 23 may be shifted to a position farther and farther away from the fulcrum 20 at each complete up-and-down movement of the yoke 27. Thus gradually-increasing resistance may be offered to the 70 lifting of the yoke, as will be well understood. If it is desired to perform two or three lifting operations without making such adjustment, it is only necessary to throw in the abutment 39 or to take care not to lower the yoke 27 a 75 distance sufficient to cause the pawls to feed, or to adjust both the pawls alike, so that neither one will be permitted by the other to impart any movement. As the hook portion 25 is permitted to disengage the teeth 26 of 80 the intermediate lever 9 every time the parts come down to a normal rest position and the initial upward movement of the yoke 27 effects the feeding forward of the lever 18, weight 23, and hook 25, such movement will 85 not be impeded by the teeth 26, even though the handle 38 has been set to such a position as to cause the hook 25 to engage the teeth 26 when the weight 23 is lifted. The lifting will take place immediately after the feeding 90 movement has been effected. The fork 22 of the lever 18 is provided with indicating-pointers 40, adapted to register with the graduations of various scales 41, provided upon an uprising portion 42 upon the platform 4. In the present instance I have shown 95 six scales, one of which is intended to be used to indicate the weight resistance when the weight 23 only is employed—that is, when the hook 25 is turned out of position to engage 100 the teeth 26 of the intermediate lever 9. The other five scales are intended to be employed to indicate the various resistances offered by the weight 8 when the link 13 is adjusted to engagement with the various studs 15 of the 105 intermediate lever 9. These various scales may correctly indicate just the resistance offered to the lifting-handle 29 or the harness 30.

A further extension of the casing is provided at 43 to inclose the rear end of the lever 18 when it is in a rearward position, and a doorway 44 is also provided with a door 45, by which ready access may be had to the lever 13 for the purpose of adjusting it as may 115 be desired. This door and doorway are shown clearly in Figs. 2 and 6.

In order to sustain the shock of the heavy weight 18, I have provided resistance means comprising two spring members 46, pivoted 120 to the base 1 of the casing and connected together by means of a rod 47 and springs 48. This means will prevent undue shock to the machine in case the weight 8 is permitted to fall too quickly.

From the foregoing description it will be seen that the machine has a wide range of applicability. By turning the handle 38 so as to throw the hook 25 out of its operative position the machine may be used for light 130

wrist and hand exercises, the weight 23 being previously adjusted to any desired position and then locked in its adjusted position by means of the abutment 39, or adjustment 5 during the use of the machine by the mere raising and lowering of the handle 29 may be effected, such adjustment being either in a direction to increase or decrease the weight resistance. Other initial adjustments may 10 also be made by shifting the yoke-piece and parts carried thereby from the position in which it is shown in the drawings to various other positions along the housing between other shoulders 28, several of which are provided, as will be seen. Heavier lifting may 15 be provided for by adjusting the hook 25 to engage the teeth 26, the resistance being again adjusted initially by means of initial adjustment of the lever 18, and also adjusted, 20 if desired, during the operation of the machine by permitting the feeding operation of the ratchet-and-pawl mechanism, as above explained, and initial adjustment may be still further effected by adjusting the position 25 of the link 13. For the heavier lifting the harness 30 may be employed, said harness being allowed to pass over the body in any desired manner, and the handles 31 may then be gripped in order to obtain a greater 30 purchase.

What I claim is—

1. An exercising-machine comprising a weighted lever, a pivotal support therefor, and a lifting member, said lifting member 35 adapted to be adjusted longitudinally upon said lever, said lever arranged to be adjusted longitudinally with respect to said lifting member and with respect to the pivotal support thereof.
2. An exercising-machine comprising a weighted lever, a pivotal support therefor, and a lifting member, said lifting member adapted to be adjusted longitudinally upon 40 said lever, said lever arranged to be adjusted longitudinally with respect to its pivotal support.
3. An exercising-machine comprising a weighted lever, a pivotal support therefor, a lifting member, and means operated by the 45 lifting member in its movement for adjusting the relationship of the weighted portion of the lever to that of the lifting member.
4. An exercising-machine comprising a weighted lever, a pivotal support therefor, a lifting member, and means operated by the 50 lifting member in its movement for adjusting the relationship of the weighted portion of the lever to the said pivotal support therefor.
5. An exercising-machine comprising a pivoted housing, a weighted lever arranged 55 to be moved longitudinally therethrough, a lifting member, and feeding means for the weighted lever operated by said lifting member.
6. An exercising-machine comprising a

pivoted housing, a weighted lever arranged to be moved longitudinally therethrough, a lifting member, and feeding means for said lever arranged to be operated by said lifting member, the said lifting member being also 70 capable of adjustment to various positions along said housing.

7. An exercising-machine comprising a pivoted housing, a weighted bar arranged to move longitudinally therethrough, a lifting member, and pawls carried by said lifting member arranged to engage said bar for feeding purposes.

8. An exercising-machine comprising a pivoted housing, a weighted bar arranged to 80 move longitudinally therethrough, a lifting member, pawls carried by said lifting member arranged to engage said bar for feeding purposes, and adjustable stops for the said pawls.

9. An exercising-machine comprising a pivoted housing, a weighted lever arranged to be moved longitudinally therethrough, a lifting member, feeding means for the weighted lever operated by said lifting member, and 90 means for locking the said lifting member to the housing, whereby the feeding means will be prevented from operating.

10. An exercising-machine comprising a pivoted housing, a weighted lever arranged 95 to be moved longitudinally therethrough, a lifting member, feeding means for the weighted lever operated by said lifting member, and a pivoted abutment for locking the said lifting member to the housing, whereby the 100 feeding means will be prevented from operating.

11. An exercising-machine comprising a pivoted housing 19, a bar 18 arranged to move therethrough, a lifting member including a yoke 27 arranged to engage the housing, and pivoted feeding-pawls 32, 33, arranged to engage the under side of the bar 18 for feeding purposes, substantially as specified.

12. An exercising-machine comprising a 110 weighted lever, a pivotal support therefor, a lifting member for said weighted lever, means for adjusting the relative positions of the fulcrum, the weighted portion and the lifting member of said lever with respect to each other, another pivoted weighted lever, and 115 an adjustable connection between the said levers.

13. An exercising-machine comprising a weighted lever, a pivotal support therefor, a 120 lifting member for said weighted lever, means for adjusting the relative positions of the fulcrum, the weighted portion and the lifting member of said lever with respect to each other, another pivoted weighted lever, and 125 means for connecting and disconnecting one said lever with and from the other.

14. An exercising-machine comprising a weighted lever, a pivotal support therefor, a lifting member for said weighted lever, means 130

for adjusting the relative positions of the fulcrum, the lifting member and the weighted portion of said lever with respect to each other, another pivoted lever, an abutment 5 for normally supporting same, and means carried by the first said lever for engaging the second said lever when the first said lever is lifted.

15. An exercising-machine comprising a pivoted lever, adjustable lifting means therefor, an intermediate lever, a weighted lever, means adjustably connecting the first said lever with the intermediate lever, and means adjustably connecting the intermediate lever 15 with the said weighted lever.

16. An exercising-machine comprising a pivoted lever, an adjustable lifting means therefor, an intermediate lever, an adjustable connection between said first-named lever 20 and said intermediate lever, a weighted lever, a link adjustably connected with said weighted lever, said intermediate lever having a plurality of fixed points to which said link may be attached.

25 17. An exercising-machine comprising a pivoted lever, an adjustable lifting means therefor, an intermediate lever, an adjustable connection between said first-named lever and said intermediate lever, a weighted lever,

a link adjustably connected with said weighted lever, said intermediate lever having a plurality of fixed points to which said link may be attached, said machine provided with a plurality of graduated scales corresponding to the varying degrees of lift represented 30 by the several fixed points of connection 35 upon the intermediate lever.

18. An exercising-machine comprising a pivoted lever having a weighted portion, a lifting means therefor, means for adjusting the relation of the fulcrum, the lifting means and the weighted portion of the lever with respect to each other, and a resistance means for supporting the weight comprising members arranged to be laterally spread against 45 yielding resistance.

19. An exercising-machine comprising a lever, a pivotal support therefor, a weight pivotally suspended from the end of the lever, a lifting member, a rod passing through 50 said weight provided at its upper end with a handle, and at its lower end with a hook, and a lever with which said hook is adapted to engage.

ADRIAN P. SCHMIDT.
